(57) **CLAIM**

The ornamental design for the wire mesh storage basket, as shown and described.

DESCRIPTION

FIG. 1 is a front perspective view of a wire mesh storage basket.

FIG. 2 is a front elevational view of the invention.

FIG. 3 is a top plan view of the invention.

FIG. 4 is a bottom plan view of the invention.

FIG. 5 is a rear elevational view of the invention.

FIG. 6 is a right side elevational view of the invention; and, FIG. 7 is a left side elevational view of the invention.
